UNITED STATES PATENT OFFICE.

WILLIAM W. DICKINSON, JR., OF LITTLE ROCK, ARKANSAS.

APPARATUS FOR BURNING BRICKS.

Application filed July 13, 1923. Serial No. 651,215.

To all whom it may concern:

Be it known that I, WILLIAM W. DICKINSON, Jr., a citizen of the United States, residing at Little Rock, in the county of Pulaski and State of Arkansas, have invented a certain new and useful Improvement in Apparatus for Burning Bricks, of which the following is a full, clear, and exact description, reference being had to the accompanying drawings.

This invention relates to the art of making bricks and has special reference to the burning of the same, the word "bricks" as herein used including tiles and other building shapes. The principal objects of the invention are the provision of new and simple expedients for saving fuel and securing a uniform burning of the brick or tile. Other objects are the provision of a construction and arrangement of kilns and their adjuncts as shall enable the repeated use of the hot gases with a minimum of permanent construction such as walls, roofs and tunnels; the provision of a continuous kiln which may be built in the open and with only the patterns of brick work most frequently used in kiln building; the provision of a new and simple form of kiln construction which shall combine the advantages of a field kiln with those of a continuous kiln and this with a maximum simplicity of construction and minimum of heat loss; the provision of a continuous kiln without tunnels in which water may condense and without permanent walls to absorb heat and impede work; the provision of a construction of continuous kiln wherein the heat is distributed uniformly; the provision of a kiln of this nature which can be used successfully with any customary fuel or any type of clay; while further objects and advantages of my invention will become apparent as the description proceeds.

In the drawings accompanying and forming a part of this specification I have shown certain preferred embodiments of my idea although it will be understood that these are illustrative only and not limiting upon me. Fig. 1 is a vertical, longitudinal sectional view through a series of kilns arranged to burn gas; Fig. 2 is a horizontal sectional view corresponding generally to the broken line

2-2 of Fig. 1; Fig. 3 is a transverse sectional view corresponding to the broken line 3-3 of Fig. 1; Fig. 4 is a side elevation of a 55 row of kilns embodying my improvements; Fig. 5 is a left hand end elevation of the structure shown in Fig. 4; Figs. 6, 7, and 8 are perspective views showing in detail the preferred patterns employed in different 60 parts; Fig. 9 shows a modification adapted for burning with oil; and Figs. 10 and 11 illustrate modifications to adapt the same for burning with coal.

In the performance of my invention I 65 build a row of kilns A, B, C, D, etc., end to end in an unbroken row as shown in Fig. 4. Preferably I employ permanent abutments or piers 1, 2 at the two ends, which may well be lined with fire brick as shown at 3 in 70 Figs. 1 and 2. The kilns are included between parallel side walls 4-4 which may if desired have a batter or inclination toward the top although I have shown them as vertical and each kiln is separated from its 75 neighbor by a cross wall 5. The outside or scove walls 4-4 may be built of large portable panels if desired, as per my Patent No. 1,403,300 but I have here shown them as built of burned bricks laid on edge with 80 their maximum dimension perpendicular to the kiln wall. The walls 5, 5 are made of unburned bricks laid on edge as shown in Fig. 6 and lengthwise of the kiln; the walls 5 are laid as tightly as possible so as to prevent 85 leakage of fluid except at the arches 6, 6 which are provided at spaced points next the ground.

Adjacent to each of the side walls 4, 4, and at one side of each of the cross walls 5, 90 I preferably lay a wall or tier 7 of unburned bricks in "cob-hacked" relation as shown in detail perspective in Fig. 7. This is a setting well known to kiln builders and consists of spaced bricks laid two over two, 95 crosswise, as in a "cob-house." Inside the space defined by these "cob-hacked" walls I lay other bricks in any of the familiar honeycomb patterns employed in kilns. The pattern I prefer is that known as "three-over-one," as shown in detail perspective in Fig. 8, two of the bricks being set close together and then two more also close together but spaced from the first two about the thickness

of a man's fingers thus affording many narrow passageways for the hot gases; although this pattern is susceptible of modification according to the fancy or habit of the builder, the nature of the clay, the dimensions of the bricks, etc. It is generally important however, to have this body portion 8 of the kiln surrounded by layers of smaller density such as the layers 7, although other 10 patterns than the "cob-hack" may doubtless be employed for the latter. The layers 7 surround only three sides of this body portion, while the fourth side is spaced from the head wall 3 and correspondingly from each 15 cross-wall 5 to define the open flues 9, 9 which extend from side to side and from top to bottom of the kiln.

The walls 4—4 may be spaced apart so as to make the kiln of any desired width, limited, 20 generally, only by the structural demands of the shed or roof with which they are generally covered. The cross walls 5, 5 are spaced from the head wall 3 and from each other any distance which experience shows to afford a uniform burning; I have found a 25 distance of from sixteen to twenty lengths of brick from the flue 9 to the cross wall 5 very satisfactory. The height is also largely a matter of choice. I have shown and in 30 practice have found very satisfactory a height of thirty courses, the top of the kiln being covered with an air tight platting 10. This platting may be done with burned 35 bricks but I greatly prefer a fire brick tile made with overlapping portions and laid two-ply with broken joints, since this can be made of sufficient size to bridge easily the flues 9, 9, which are preferably made some ten to twelve inches wide.

The upper courses of brick in the kiln body are preferably columns 11 and passageways 12 running from the flue 9 to the cob-course adjacent the cross-wall, and the platting is laid on top of these columns. 45 The platting and scoving is preferably daubed with mud to minimize air leak, and the portions of the scoving opposite the flues 9 are preferably displaced therein as shown at 13 so as to break joints with the cross walls 5. Each flue is also formed at each 50 side with a removable portion 15 adapted for the reception of the intake pipe 16 of an exhaust fan 17 operated by an electric motor 18 or other power device, and having 55 a discharge pipe 19. These fans are movably supported as by the trucks 20, 20 so as to be shifted from kiln to kiln as the burning progresses.

When gas is to be used for fuel a small 60 tunnel 24 is constructed beneath each flue, and the bottom of each flue is made of tile 25 having opposite each of the arches 6 an aperture 26 in which is located a gas pipe 27, each of the pipes having a separate control 65 valve 28 outside the kiln. The head wall

is formed with inlet openings 29 opposite the different gas jets. Also as the kiln is built each of the arches 6, 6 is covered with a flap of paper 30, as shown in Fig. 1, preferably fastened into the wall at the top and hanging freely in the flue like a check-valve.

Any desired number of kilns can be built in a row; the full value of my invention is not secured with less than seven kilns and 75 the best number is from twenty to forty or even more. In practice a number of kilns are built in substantially the manner described beginning with A in Fig. 4. The exhaust fans are attached to the openings 80 15, 15 of kiln B and a low fire started in the first flue. The paper flaps 30 in the flue of kiln C prevent any back flow of air 85 and the construction of the kiln with its maximum looseness at the walls and top causes the hot gas to pass through the whole mass with substantial uniformity. At the end of a day or two, dependent upon the fire, the water content of the bricks, and the drying nature of the clay (all of which depend upon the peculiarities of the clay since some clays will stand more heat than others), the moisture content of the issuing gases generally falls to such a point that the 90 fans may be moved to the openings 15, 15 of kiln C, thereby utilizing the drying power of those gases to the utmost; and often times the fan will be moved to kiln D before the temperature of kiln A has risen to burning 95 temperature. During this period the fuel supply to kiln A has gradually been increased until the bricks therein have been burned thoroughly, whereupon the gas is turned onto the burners of kiln B and the 100 burners of kiln A are shut off. It now becomes possible to burn kiln B with much 105 less fuel than kiln A, both because of its long preheating and because of the fact that the entering air is itself preheated by the hot bricks in kiln A. When the burning in 110 kiln B is complete the fire is advanced to kiln C and the air drawn through both kiln A and kiln B, the fan being always advanced so that the gases issuing therefrom are as 115 nearly saturated as possible. I have had the best results as regards fuel economy when drawing the air through three kilns in advance of the burning one and three more after passing the burning one, or seven kilns 120 in all, but this is likely to vary with different clays, and different fuels, and possibly with different sizes of kilns.

As soon as the burned kilns are so far 125 cooled that the heat derivable from them is less than the power required to draw the air through them, the wall 13 of the next flue is broken down, after which the preceding kiln can be torn down, which is effected from the outside, all parts being loaded out except the platting which is transferred 130

down the line; with the result that the kiln row may exhibit kilns being built, dried, preheated, burned, cooled, and loaded out, all at the same time. Generally the most convenient practice is so to gauge the size and rapidity of burning the kilns that the fire is advanced each day, although I do not exclude the possibility of having fire in two or more adjacent kilns at the same time. As the foot end of the row is approached the fire necessarily approaches more nearly to the fan, and the latter is protected from injury either by drawing the gases through a cooling chamber such as a kiln X left standing continuously for the purpose (and built of unmerchantable bricks) or by allowing such an admission of cold air to the fan as shall temper the hot gases. Also enough cold air is admitted to the different tunnels 24, to protect the gas pipes; or the latter can be drawn a distance below ground since the gas does not ordinarily burn until some distance from the jet.

When oil is used for fuel no tunnels are necessary, but hollow casings 32, 32 are provided at opposite ends of each of the flues 9, and the jet pipes 33, 33, trained therein along with steam pipes 34 by which the flames are driven horizontally into the flues as far as desired; and in case of need other casings 35 and jets 36 are inserted higher up in each flue.

In order to use coal for fuel the top of each flue is provided above each arch 6 with a funnel 40 adapted to be closed by a removable cover 41 through which coal in small quantities is dropped at intervals. When coal of good quality is used no bottom draft is needed, the coal burning freely in the air entering through the arches 6, but when inferior coal is employed it is sometimes desirable to provide small tunnels 42, roofed with fireclay tiles 43 formed with slits 44. The paper flaps are used in all cases, preventing the air from being drawn back through kilns in front of the fan, while being easily displaced when the fan is moved beyond them and being consumed when the fire reaches them. The heat from each kiln is also sufficient to ignite the fuel in the next succeeding kiln.

It is within my invention to modify the pattern of the bricks at different points if desired for the purpose of controlling or directing the gas flow. For example it may sometimes be desirable to lay the first tier of bricks adjacent the flues somewhat more closely at the bottom to discourage the gas from cutting across; but in general I prefer to build the kiln interior of as uniform texture as possible to the end that it may settle uniformly and without markedly changing the course of the gases as the burning proceeds, although the shrinkage of the bricks in the cross walls 5 is to some extent

advantageous in that it tends to draw the fire in that direction and hence to burn the upper corner of the kiln adjacent thereto.

By avoiding the use of permanent walls I both decrease expense of construction and maintenance, facilitate the building and loading out of the kilns which can thus be done in the opening, and avoid the waste of heat otherwise absorbed by permanent structures; by dispensing with separate air ducts such as tunnels I avoid the condensation of water and the deposition of dust therein, both of which would otherwise have to be removed. The described apparatus cuts the fuel cost to less than half and expedites the tearing down of kilns by accelerating their cooling thereby increasing the output of a given size of plant. But there are many changes in detail which may be made within the scope of my invention and I do not limit myself except as recited in the annexed claims, neither do I limit myself to blocks of any one shape nor do I exclude tile and other articles but include all under the generic term of "brick". Also while I have shown the flues 9 as wholly unobstructed I do not exclude a partial obstruction of the same since my invention is not avoided merely by impairing it in some degree. Also I do not limit myself to the use of portable fans to produce the suction since stationary fans can be employed, and connected to the different kilns by tunnels or conduits.

Having thus described my invention, what I claim is:

1. In kiln construction, the combination with parallel side walls, of cross walls connecting the same and having openings at their bottoms, bricks built within said walls in open-work relation, said bricks spaced from one side of each cross wall to define an open flue with which said openings communicate, and said walls being built up with and supported by and removed with said bricks, means for drawing air through successive kilns, and means for burning fuel in said flues in front of said openings.

2. Brick burning apparatus comprising, in combination, a plurality of field kilns built in a row, each kiln comprising a body of bricks hacked in open relation surrounded and separated from adjacent kilns by temporary walls supported by said bricks, there being an open flue at the side of each kiln adjacent to the neighboring kiln and a comparatively tight wall at the opposite side, the lower portion of such wall having one or more openings adapted to communicate with the flue of the next kiln, and means for introducing combustible material into said flues.

3. Brick burning apparatus comprising, in combination, a plurality of field kilns built in a row, each kiln comprising a body of bricks hacked in open relation surround-

- ed and separated from adjacent kilns by temporary walls supported by said bricks, there being an open flue at the side of each kiln adjacent to the neighboring kiln and a comparatively tight wall at the opposite side, the lower portion of such wall having one or more openings adapted to communicate with the flue of the next kiln, and means for connecting a suction device to the side wall of each flue. 10
4. Brick burning apparatus comprising, in combination, a plurality of field kilns built in a row, each kiln comprising a body of bricks hacked in open relation surrounded and separated from adjacent kilns by temporary walls supported by said bricks, there being an open flue at the side of each kiln adjacent to the neighboring kiln and a comparatively tight wall at the opposite side, the lower portion of such wall having one or more openings adapted to communicate with the flue of the next kiln, valve means permitting a flow of air from each kiln to the flue of the next kiln while preventing a return flow, and means for connecting a suction fan to the side wall of each flue. 20
5. Brick burning apparatus comprising, in combination, a plurality of heaps of loosely piled bricks, impervious top and lateral walls embracing the same, and cross walls separating them, said cross walls impervious except at the bottom, each cross wall having at one side a substantially open flue, means for attaching a suction fan to any flue, and means for introducing combustible material into any flue, all of such walls being supported by and dismantled with said loosely piled bricks. 30
6. Brick burning apparatus comprising, in combination, a plurality of rectangular heaps of loosely piled bricks, spaced apart in a row, impervious walls embracing said piles on all sides and supported thereby, the cross walls being spaced from the bricks at one side of the same to define a flue therewith and having openings at the bottom into such flue, a movable suction device adapted to be attached to any flue, and means for introducing combustible material into any flue. 40
7. Brick burning apparatus comprising spaced impervious side walls and top wall, and cross walls of bricks to be burned, the latter arranged in transverse partitions which are tight excepting at the bottom, and interspersed piles of bricks to be burned so loosely packed as to enable uniform percolation of gases therethrough, each pile being located closely adjacent to one partition and spaced from the next partition to form a transverse flue which reaches from the bottom of said kiln to the top wall in combination with suction devices to draw such gases through successive piles and means for feed- 50
- ing combustible material adjacent to said transverse partitions, said walls engaging said loosely packed bricks in supported relation. 60
8. Brick burning apparatus comprising, in combination, a plurality of field kilns built in a row and having substantially impervious scoving and platting, each kiln being separated from the next kiln by a transverse wall which is built up anew with each kiln and is substantially impervious except for spaced apertures and each kiln also having a closable lateral opening in its scoving, combustible valves for preventing back flow through such apertures while permitting direct flow, and a portable exhaust device adapted to have its intake connected to any one of said lateral openings. 70
9. Brick burning apparatus comprising, in combination, a plurality of field kilns built in a row and having substantially impervious scoving and platting, each kiln being separated from the next kiln by a transverse wall which is substantially impervious except for spaced apertures and each kiln also having adjacent to said transverse wall an open flue which extends from bottom to top thereof, the scoving being formed with a closable exhaust opening for each of said flues, and suction producing apparatus adapted to be connected to any of said exhaust openings in draft producing relation. 80
10. Brick burning apparatus of the continuous type comprising a row of field kilns having substantially impervious side walls and spaced cross walls, the latter having flues at one side and openings at the bottom, the kilns having substantially impervious top walls carried by the bricks to be burned and said openings constituting air inlets and said flues constituting combustion and up-draft chambers. 90
11. Brick burning apparatus of the continuous type comprising a row of field kilns having substantially impervious side walls and spaced cross walls, said cross walls being pervious at the bottom and impervious at the top and the bricks in the separate chambers so defined being hacked with increasing porosity toward the top, said bricks being spaced from said side walls at one side to define combustion and up-draft chambers, and substantially impervious roofs carried by the bricks to be burned. 100
12. Continuous process brick burning apparatus of the field kiln type characterized by having continuous side and top walls and spaced cross walls, the latter being substantially impervious except adjacent to the bottom and spaced from the bricks at one side to define combustion and up-draft chambers, said bricks being hacked with increasing looseness toward the top, and means for creating suction in flues subsequent to the first flue. 110
- 130

13. Continuous process brick burning apparatus of the field kiln type characterized by having continuous side and top walls and spaced cross walls, the latter being substantially impervious except adjacent to the bottom and spaced from the bricks at one side to define combustion and up-draft chambers,

said bricks being hacked in loose burner relation throughout the body of each chamber, and piled with increased looseness adjacent to the walls and roof. 10

In testimony whereof, I hereunto affix my signature.

WILLIAM W. DICKINSON, JR.
